BUCKEYE STEEL CASTINGS CO., OF COLUMBUS, OHIO.

BRAKE-HANGER SUPPORT FOR TRUCKS.

1,415,132.

Specification of Letters Patent. Patented May 9, 1922.

Application filed April 12, 1920. Serial No. 373,196.

To all whom it may concern:

Be it known that we, JOHN C. WHITRIDGE and JACOB C. LARSEN, citizens of the United States and Denmark, respectively, and residents of Columbus, in the county of Franklin and State of Ohio, have invented certain new and useful Improvements in Brake-Hanger Supports for Trucks; and we do hereby declare the following to be a full, clear, and exact description of the invention, such as will enable others skilled in the art to which it appertains to make and use the same.

Our invention relates to an improvement in brake hanger-supports for trucks and particularly six wheel trucks, and is designed particularly as an improvement on the construction shown in patent to Larsen No. 1,298,228 dated March 25th, 1919.

20. In the Larsen patent the brake hanger supports are secured to a bracket on a shelf, the shelf and bracket being cast integral with the bolster spring seats. With the Larsen improvements the truck side frames are necessarily made for right and left hand sides and the construction is such that the bolster opening cannot be made to receive a bolster having integral column guides.

The object of the invention is to provide 30 a construction that eliminates the necessity for right and left hand patterns for the side frames; makes possible the use of the regular side frame construction at the bolster openings so as to permit the use of bolster 35 with integral or fixed column guides, and greatly simplifies the operation of casting the side frames.

With these objects in view, our invention consists in the details of construction 40 as will be more fully described and pointed out in the claims.

In the accompanying drawings, Figure 1 is a view in plan showing one side of a truck, part of the other side being broken away; 45 Figure 2 is a view partly in end elevation and partly in section of the truck; Figure 3 is a view in transverse section on the line 3—3 of Figure 1 and Figure 4 is a similar view on the line 4—4 of Figure 1.

50. The invention is applicable for use with various types of six wheel trucks, and while we have illustrated this improvement in connection with the side frames used in truck design, patented to Larsen and John-

son No. 1,253,842 dated January 15th, 1918, 55 we have done so for the purpose of illustration only and not with the intention of limiting its application to such side frame or any other particular construction of side frame.

6 represents the truck side frames, there 60 being two to each side, with their adjacent ends overlapping as shown in Fig. 1, for the connection therewith of the frames 7 carrying the bearings for the center axle 8. Each side frame 6 has a bearing for a journal of an end axle, and each is also provided with an opening 10 for the reception of one end of a transverse or auxiliary bolster 11, each bolster 11 being yieldingly supported 70 adjacent its ends, on springs 12 seated within the openings 10. The transverse bolsters 11 are located as shown, one between the front and middle axles, and the other between the rear and middle axles, and support the longitudinal bolsters 13, each of 75 the latter having bearing at its ends on the transverse bolsters 11, between the shoulders 14 on the latter as shown in Fig. 1, and each of said longitudinal bolsters 13 is provided with the shoulders 15, which prevent their 80 endwise movement on the transverse bolster 11.

The main bolster 16, is in the present instance, located over the central axle 8, and is supported at its opposite ends in openings 85 in the two longitudinal bolsters 13 (see Fig. 2), and is held against endwise displacement by the shoulders 18 as shown in Figure 3 which bear against the inner faces of the longitudinal bolsters 13. With this construction the weight of the center bolster 16 and the load thereon, will be sufficient to retain the bolsters in position without further securing devices other than the shoulders or 90 lugs previously referred to.

The bolster openings 10 in the side frames are widened at the bottom as shown in Figure 2 to permit the bolster 11 having integral column guides 11^a therein to be entered at the bottom and when elevated and seated on the springs 12, these column guides 11^a embrace the side walls of the openings 10 above the widened part of the latter and are thus held against endwise movement and operate to prevent any 105 spreading of the side frames.

Secured within the bolster openings 10 in the side frame and at the bottoms of said

openings are the spring seats 19 having the integral brackets 20 to which the brake hangers are secured. These spring seats may be bolted or riveted to the side frames, 5 as shown in Figure 4 hence may be placed in position and secured in place after the bolster 11 has been assembled, and after they have been secured they form the seats for the bolster carrying springs 12 which assist in holding the seats 19 in position. 10 These brackets 20 extend inwardly horizontally in a plane slightly above the spring seats 19 and are located in a plane between the wheels as shown in Fig. 2 and form supports for the brake hanger brackets 21 which are cast integral with the spring seats 19.

With this construction it will be seen that by using a spring seat carrying brackets for 20 the brake hangers, made separate from the side frames, the latter can be constructed with bolster openings to receive bolsters having fixed or integral column guides and the spring seats secured in place after the 25 bolsters have been assembled, and it also eliminates the use of right and left hand patterns for the side frames.

It is evident that many slight changes 30 might be resorted to in the relative arrangement of parts shown and described without departing from the spirit and scope of our invention. Hence we would have it understood that we do not wish to confine our-

selves to the exact construction and arrangement of parts shown and described, but 35

Having fully described our invention what we claim as new and desire to secure by Letters-Patent, is:—

1. In a railway truck, the combination of a side frame having a bolster opening, a 40 spring seat removably secured to the side frame at the base of said opening and a brake hanger support carried at the inner edge of said spring seat.

2. In a railway truck, the combination of 45 a side frame having a bolster opening and a combined spring seat and brake hanger support separate from and secured to said side frame at the bottom of the bolster opening, the brake hanger support projecting inwardly and upwardly from the seat.

3. In a railway truck, the combination of 50 a side frame having a bolster opening and a spring seat separate from and secured to the side frame within the bolster opening, the said spring seat having an integral inwardly projecting brake hanger support.

In testimony whereof, we have signed this specification in the presence of two subscribing witnesses.

JOHN C. WHITRIDGE.
JACOB C. LARSEN.
